UNITED STATES PATENT OFFICE.

ARTHUR ST. CLAIR BUTLER, OF RICHMOND, VIRGINIA.

DESIGN FOR A PITCHER.

SPECIFICATION forming part of Design No. 24,238, dated April 23, 1895.

Application filed January 16, 1895. Serial No. 535,152. Term of patent 7 years.

To all whom it may concern:

Be it known that I, ARTHUR ST. CLAIR BUTLER, a citizen of the United States, residing at Richmond, in the county of Henrico and State of Virginia, have invented a certain new and original Design for an Original Package for Tobacco, of which the following is a specification, reference being had therein to the accompanying drawings.

10 My invention relates to a design for a pitcher, and its leading feature consists in having its body enlarged or bulged midway its length, the portion of the body below the bulge being tapered straight down to the bottom of the pitcher and the portion of the body above being tapered straight up to the top, the upper and lower ends being equal in diameter, and the upper end being provided with an outwardly-flaring annular flange which projects 15 upwardly and has its upper edge curved, substantially as herein shown.

In the drawings, Figure 1 is a perspective view of my new design, and Fig. 2, a side elevation thereof.

The body A has its greater diameter midway its length, the lower part of the body tapering straight down to the bottom of the vessel and the upper part tapering straight up to the upper end or neck thereof, where it connects with the outwardly-flaring upwardly-extending flange B, which has its upper edges curved down on opposite sides of the handle D which connects said flange to the body of the vessel. The lower end *a* and the upper end or neck *b* of the vessel are of the same 35 diameter and the central ridge or bulge *c* in the body is about midway between the upper and lower ends. The cover C fits within the neck, below the upper edge of the flange B.

What I claim is—

40 The design for a vessel herein shown and described.

In testimony whereof I affix my signature in presence of two witnesses.

A. ST. CLAIR BUTLER.
